CLAIM

The ornamental design for a portable multi-port liquid adapter, as shown and described.

DESCRIPTION

FIG. 1 is a perspective view of a portable multi-port liquid adapter showing my new design;

FIG. 2 is a front elevation view thereof;

FIG. 3 is a rear elevation view thereof;

FIG. 4 is a side elevation view thereof;

FIG. 5 is a top elevation view thereof; and,

FIG. 6 is a bottom elevation view thereof.

The broken lines in FIG. 1 are for purposes of illustration only and form no part of the claimed design.
